(57) **CLAIM**

(21) Appl. No.: **29/274,486**

The ornamental design for a washing machine for medical and surgical instruments, as shown.

(22) Filed: **Apr. 27, 2007**

DESCRIPTION

(30) **Foreign Application Priority Data**

Oct. 30, 2006 (EM) 000613591-0001

FIG. 1 is a perspective view of the washing machine for medical and surgical instruments.

(51) **LOC (8) Cl.** **24-02**

FIG. 2 is a front view of the washing machine for medical and surgical instruments.

(52) **U.S. Cl.** **D24/217**

FIG. 3 is a back view of the washing machine for medical and surgical instruments.

(58) **Field of Classification Search** D24/216-234;

FIG. 4 is a right side view of the washing machine for medical and surgical instruments.

422/26-28, 31, 292, 293, 300-301, 305,

422/114, 116, 295, 297; 134/95.2; D32/1

See application file for complete search history.

FIG. 5 is a left side view of the washing machine for medical and surgical instruments.

(56) **References Cited**

FIG. 6 is a top view of the washing machine for medical and surgical instruments; and,

U.S. PATENT DOCUMENTS

FIG. 7 is a bottom view of the washing machine for medical and surgical instruments.
